UNITED STATES PATENT OFFICE.

HAROLD M. SCHEIBE, OF WILKINSBURG, PENNSYLVANIA, ASSIGNOR TO WESTINGHOUSE ELECTRIC AND MANUFACTURING COMPANY, A CORPORATION OF PENNSYLVANIA.

SPARK-TIMER.

1,074,984.

Specification of Letters Patent.

Patented Oct. 7, 1913.

Application filed November 8, 1911. Serial No. 659,220.

To all whom it may concern:

Be it known that I, HAROLD M. SCHEIBE, a citizen of the United States, and a resident of Wilkinsburg, in the county of Allegheny and State of Pennsylvania, have invented a new and useful Improvement in Spark-Timers, of which the following is a specification.

My invention relates to combined interrupters and spark timers for use with internal combustion engines, and it has for its object to provide a simple and effective device for simultaneously adjusting both the degree of advance of the spark produced by the interrupter with relation to the engine piston and the distance between the interrupter contact members, so that the periods of engagement thereof may be made substantially uniform at all engine speeds.

My invention is illustrated in the accompanying drawing, Figure 1 of which is a vertical sectional view through a combined interrupter and spark advancer that is constructed in accordance therewith, and Fig. 2 is a view in end elevation and in section of the device shown in Fig. 1.

My invention is adapted to be employed in connection with any constant-pressure source of current for ignition or other purposes, and to be driven by the engine at the proper speed, it being shown in the present instance as mounted at the end of the shaft 1 of a small generator.

The device comprises a cam 2 that is secured in any suitable manner upon the end of the shaft 1, and, except for two small diametrically opposite recesses, is of substantially cylindrical contour, with its axis coincident with the axis of the shaft. The cam 2 is surrounded by a cylindrical sleeve 4 that is formed integral with, or is otherwise suitably secured to, an end bracket 5 of the generator, its lower right-hand portion being omitted or cut away for something more than 90 degrees. The sleeve 4 is eccentrically disposed with respect to the shaft 1 and the cam 2, its axis being indicated at 3. The sleeve 4 is closely surrounded by, and serves as a bearing for, a cylindrical portion 6 of a shell or frame 7 that is provided with arms or lugs 8 for the attachment of means, whereby the shell or frame may be manually rotated by the driver or operator.

Pivotaly mounted within the shell or frame 7, is a small bell crank lever 9 having a substantially vertical forked arm 10 in which is mounted a roller 11 that bears against the outer surface of the cam 2. A substantially horizontal arm of the bell crank lever 9 carries a contact member 12 that is adapted to engage with the upper end of a screw 13, carried by, but insulated from, the shell or frame 7, the said screw being adjustable for the purpose of varying the distance between it and the member 12 in order that the proper operation of the device may be insured. To this end, the screw should be so adjusted that the roller 11 will just seat itself in the recesses in the cam 2 when the contact terminal 12 engages the upper end of the screw, and the remaining arts occupy the positions shown, which are for fully-retarded spark conditions. A spring 14 serves to resiliently press the roller 11 into engagement with the surface of the cam 2, and to cause the contact terminal 12 to engage the end of the screw 13 when the roller drops into one of the recesses in the cam. A cover 15 for the shell or frame 7 is retained in position by means of a spring 16 that is carried by the end bracket 5 of the generator.

In the operation of the device, the frame 7 occupies the position shown when the engine is not in operation or is operating at slow speeds, and, as the speed of the engine increases, the operator or driver manually moves the same in order to advance the position of the roller 11 so that it will drop into the recesses in the cam earlier in its period of rotation, thereby advancing the spark with respect to the engine pistons. At the same time the roller 11 is moved farther away from the axis of rotation of the cam, since it turns about the axis 3, rather than about the axis of the cam. The contact terminal 12 is then located closer to the end of the screw 13 when the roller 11 bears upon the cylindrical portions of the cam, and, consequently, it is required to move a less distance in order to engage the end of the said screw than previously. The degrees of angular movements of the cam during which the roller 11 occupies the recesses therein, of course, remain the same, irrespective of the position of the roller as determined by the position of the frame 7, but since the

contact terminal 12 is required to move a shorter distance in order to engage the screw 13, it will engage sooner and disengage later when the roller 11 is advanced in position, 5 and consequently longer, than when it occupies the position shown. The periods of engagement of the said contact terminal may, accordingly, be maintained substantially uniform at all engine speeds by the 10 proper adjustment of the position of the frame 7.

I claim as my invention:

1. A spark timer comprising a rotatable cam, and a switch member actuated thereby 15 and adjustable bodily in eccentric-relation with respect thereto.

2. A spark timer comprising a rotatable cam having a plurality of recesses but being otherwise of cylindrical contour, and a pivotally mounted switch member that is actuated by the cam and is adjustable bodily 20 about an axis that is eccentric with respect to the axis of rotation of the cam.

3. A spark timer comprising a rotatable 25 cam, a sleeve surrounding the cam, the axis

of which is eccentric with respect to the axis of rotation of the cam, a movable frame mounted upon the said sleeve, and a switch member pivotally mounted in said frame and actuated by the cam.

4. A spark timer comprising a rotatable cam, a circuit making and breaking switch one of the members of which is actuated by said cam, and a support for said switch that is rotatively adjustable about said cam 35 upon an axis which is eccentric to the cam axis.

5. A spark timer comprising a rotatable cam, and a circuit making and breaking switch the movable member of which is actuated by said cam and is also eccentrically and independently adjustable with reference to the cam axis.

In testimony whereof, I have hereunto subscribed my name this 31st day of Oct. 45 1911.

HAROLD M. SCHEIBE.
